(Cl. D7—5)

To all whom it may concern:

Be it known that I, Albert A. Esterson, a citizen of the United States, residing at the city of Baltimore, State of Maryland, have invented a new, original, and ornamental Design for a Shoe Sole, of which the following is a specification.

Reference is had to the accompanying drawing, forming a part of this specification, and wherein:

Figure 1 is a plan view of the bottom surface of a shoe sole, showing my new design;

Figure 2 is a side elevation;

Figure 3 is a longitudinal section taken on line 3—3 of Figure 1, and

Figure 4 is a transverse section taken on line 4—4 of Figure 1.

The dominant features of the design are the smooth, plane surface configuration of the sole,

the two, arcuate bands of slightly convex shape separating the toe from the central portion of the sole, the circular inserts and the upwardly curved rear portion adjacent the shank.

I claim:

The ornamental design for a shoe sole, substantially as shown and described.
